UNITED STATES PATENT OFFICE.

IRVING RODNEY PARSONS, OF CHICAGO, ILLINOIS.

DESIGN FOR AN ENVELOPE.

Application filed October 17, 1922. Serial No. 4,001. Term of patent 14 years.

To all whom it may concern:

Be it known that I, IRVING RODNEY PARSONS, a citizen of the United States, residing at Chicago, in the county of Cook and State of Illinois, have invented a new, original, and ornamental Design for an Envelope, of which the following is a specification, reference being had to the accompanying drawing, forming part thereof.

The figure is a plan of an envelope showing my new design.

I claim:

The ornamental design for an envelope as shown.

IRVING RODNEY PARSONS.
